UNITED STATES PATENT OFFICE.

WATT ALEXANDER HENDERSON, OF BIRMINGHAM, ALABAMA.

ACETYLENE-GAS GENERATOR.

Application filed July 28, 1926. Serial No. 125,523.

This invention relates to acetylene gas generators and has for its object the provision of a novel gauge device adapted to be connected with or to be embodied in a gas generating mechanism for the purpose of indicating, visibly, the amount of calcium carbide within the hopper at all times, it being consequently unnecessary for the operator or attendant to make an actual local inspection.

An important and more specific object is the provision of a gauge device which may be operated by pneumatic or hydraulic pressure and which is operatively connected with the hopper for the calcium carbide so that variations in the weight of the carbide within the hopper will be registered in the indicator or gauge.

An additional object is to provide a device of this character which will be comparatively simple and inexpensive in manufacture, easy to use, positive in action, efficient and durable in service, and a general improvement in the art.

With the above and other objects and advantages in view, the invention consists in the details of construction, and the arrangement and combination of parts to be hereinafter more fully described and claimed, and illustrated in the accompanying drawings, in which:—

Figure 1 is a vertical longitudinal section through an acetylene gas generator having the invention embodied therein,

Figure 2 is a detail view of one of the bellows-like elements forming part of the apparatus,

Figure 3 is a view similar to Figure 1 showing a modification, and

Figure 4 is a detail view of the hopper support embodied in the modification disclosed in Figure 3.

Referring more particularly to the drawings, the numeral 10 designates, generally, an acetylene gas generator embodying a water tank 11 above which is mounted a hopper 12 which contains the calcium carbide indicated at 13. This hopper is shown as having the usual type of filling opening 50 normally closed by a removable cap 14 so that the supply may be replenished from time to time as occasion arises.

It is well known that in acetylene gas generators, there are alternative constructions provided. In one type of device, water is permitted to drop upon the calcium car-

bide and in the other general type the calcium carbide itself is permitted to drop into water and it is in connection with the latter mentioned type that the present invention has its greatest adaptability. Obviously, the generator 10 is provided with the usual gas outlet 14 within which or with which is arranged any ordinary or preferred type of control valve structure indicated at 15.

In accordance with the present invention, the hopper 12 is vertically movably mounted and carries one or more outwardly extending bracket elements 16 engaging upon the upper ends of one or more plungers or stems 17 at the upper ends of one or more bellows members 18 mounted upon suitable brackets 19 secured to the inside of the generator in any desired manner.

Any desired number of bellows members 20 may be provided, and regardless of the number thereof, I provide pipes or tubes 20 connected and communicating therewith and connected with a common tube or pipe 21 which leads to an indicator or gauge 22 located at some convenient point. In actual practice, it is contemplated that this gauge have an illuminated dial or else that it be provided with an illuminated hand or pointer movable over a dial so that readings may be readily made at night. Sometimes devices of this character are located in places which are not well lighted, and in order that the gauge may be conveniently read both by day and by night, without the aid of artificial light, it is contemplated that the dial, or else the hand or pointer, be made luminous.

Obviously, the bellows members 18 together with the tubes or pipes 20 and 21 may contain merely air or they may contain a liquid depending upon whether the device is intended to be pneumatically or hydraulically operated. Regardless of whether these elements contain air or liquid, it is quite apparent that the weight of the hopper 12 and the contents thereof will be sustained by the bellows members 18 owing to the provision of the outstanding bracket members 16 which engage upon the stems or plungers 17. Clearly, when there is the maximum weight of calcium carbide within the hopper 12 the pressure thereof coming against the bellows members 18 will compress the air or liquid therein, as the case may be and give a corresponding indication on the gauge 22. As the calcium carbide is used up in the operation

of the generator it is obvious that the weight thereof will be reduced from time to time and the reduction in the weight will be correspondingly shown on the gauge 22 so that the operator or attendant may at any time by glancing at the gauge be apprised of exactly the amount of calcium carbide remaining in the hopper. It will consequently be unnecessary to make a local inspection and this will be a great safeguard inasmuch as it is a common practice to look at such devices with a lit match, explosions often occurring as the result thereof. The device will consequently act as a safeguard against fire in addition to having the advantage of enabling the operator or attendant to know exactly and accurately the quantity of gas forming material on hand at all times.

In Figures 3 and 4, I have illustrated a modified form of the invention in which there is provided only a single bellows member 25 mounted in exactly the same manner as the bellows members 18 of the first described form. The hopper 26 of Fig. 3 corresponding exactly to the hopper 12 of Fig. 1, is capable, of course, of vertical movement but is differently mounted inasmuch as instead of providing it with two bracket members 16 as disclosed in the first form it is supported upon a ring-like member 27 which is hinged at 28 upon one side of the shell and which is provided at a point diametrically opposite the hinge with an extension 29 resting upon the central element 30 of the bellows member 25. The member 27 is of course of ring-like formation or provided with an opening 31 for the reception of the hopper, and at opposite points the ring member is formed with inward projections 32 engaging the hopper, the purpose being to reduce the area

of engagement of the hopper with the ring member.

By the above described specific mounting for the hopper in the modified form of the invention it is clear that the hopper will be constrained to a purely longitudinal movement and cannot run laterally owing to the provision of the ring member 27 mounted in the particular manner set forth. In other words the hopper cannot cant or tip sideways and consequently interfere with the accuracy of the operation. Of course, this form of the device operates in substantially the same manner as the first described form and it is thought that a repetition of the various details is consequently unnecessary.

Having thus described the invention, I claim:

1. In an acetylene gas generator embodying a substantially vertically movably mounted carbide hopper, a stationarily mounted bellows containing fluid under pressure, means carried by the hopper for applying pressure upon the bellows, a gauge, and a fluid pressure conducting pipe leading from the bellows and connected with the gauge.

2. In an acetylene gas generator embodying a casing, a substantially vertically movably mounted carbide hopper within the casing, a bracket member carried by the hopper, a stationary support within the casing, a normally expanded bellows mounted on the support and engaged by said bracket, said bellows containing fluid under pressure, a gauge, and a conduit member leading from the bellows to the gauge.

In testimony whereof I affix my signature.

WATT ALEXANDER HENDERSON.
